UNITED STATES PATENT OFFICE

MINNIE V. SHANE, OF SAN ANTONIO, TEXAS, ASSIGNOR OF ONE-HALF TO CHARLES H. WINTERBORNE, OF SAN ANTONIO, TEXAS

MANICURIST'S THUMB GUARD

Application filed July 17, 1929. Serial No. 379,007.

This invention relates to a manicurist's appliance and more particularly to a thumb guard adapted to be worn by a manicurist when filing a person's nails.

- 5 When a person's hands are being manicured, the customer sits at one side of a table and the manicurist at the other side. The manicurist holds the fingers of the customer's hand so that the nails may be easily trimmed and filed and it has been found that when using the file it will very often strike the thumb of the manicurist's hand and scar the nail or injure and disfigure the skin about the nail.
- 10 Therefore, one object of this invention is to provide a guard or shield which may be placed upon the thumb of the manicurist's hand with which she holds the customer's finger and prevent a file having contact with the thumb or its nail when the file is in use.
- 15 Another object of the invention is to so form the guard or shield that it may have proper fit upon thumbs of various sizes and be prevented from turning about the thumb
- 20 out of its proper position.
- 25 Another object of the invention is to prevent the shield from moving rearwardly upon the thumb beyond a position in which it can very effectively shield the nail and end of the thumb.

The invention is illustrated in the accompanying drawing, wherein

Figure 1 is a perspective view showing the shield in use,

Fig. 2 is an enlarged view showing the shield in side elevation,

Fig. 3 is a front elevation of the shield, and

Fig. 4 is a longitudinal sectional view through the shield.

- 30 This shield is intended for use by a manicurist and is to be placed upon the thumb 1 of the manicurist's left hand 2 so that when holding a finger of a customer's hand 3 and filing the nail with a nail file 4 held in the manicurist's right hand the nail file will be prevented from striking the manicurist's thumb and scarring the nail or injuring the skin about the nail. This guard or shield, which is indicated in general by the numeral 5, is preferably formed of metal, although

any material found suitable may be used and consists of a plate 7 having a thumb encircling band 8 at its rear or inner end. The plate 7 is of sufficient length to cover the manicurist's thumb nail and the end of the thumb and is curved transversely, as shown in Fig. 3, so that it will fit properly against the thumb in covering relation to the nail when in use. Arms 9 extend from opposite sides of the plate 7 at its rear end and these arms are curved longitudinally to form the band 8. The arms terminate in spaced relation to each other to form a split 10 in the band thereby allowing the band to have expansion and contraction. Therefore, the band will have resiliency and the shield may be placed upon thumbs of various sizes and when in place fit snugly and grip the thumb sufficiently tight to prevent the shield from turning upon the thumb. It will thus be seen that the plate will be retained in proper covering relation to the nail. It is also desired to prevent the shield from being thrust too far upon the thumb or slipping rearwardly when in use and, therefore, the outer end of the plate is bent downwardly, as shown at 11, to form an abutment adapted to bear against the outer end of the thumb.

When this shield is in use, it is placed upon the thumb of the manicurist's left hand and the manicurist holds a finger of the customer's hand, as shown in Fig. 1. The nail file is held in the right hand and operated in the usual manner. The nail of the manicurist's thumb and portions of the skin about the nail are covered by the shield and, therefore, the file cannot strike the manicurist's thumb nail or the skin about the nail and cause the nail to be scarred or the skin of the thumb injured.

Having thus described the invention, I claim:

1. A manicurist's thumb guard comprising a plate curved transversely, and means to retain the plate in place upon a thumb with the plate in covering relation to the nail and its outer end projecting from the thumb and formed with a portion to engage the end of the thumb and limit inward movement of the guard when set in place.

2. A manicurist's thumb guard comprising a plate curved transversely and having its outer end portion bent downwardly to form an abutment, and arms extending from 5 opposite sides of said plate and bent to form an expansible band adapted to fit about a thumb and retain the plate thereon in shielding relation to the nail with the abutment engaging the end of the thumb.

10 In testimony whereof I affix my signature.
MINNIE V. SHANE. [L. S.]
